(57) **CLAIM**

I claim the ornamental design for the bagel plate, as shown and described.

DESCRIPTION

FIG. 1 is a top view of a bagel plate wherein the left and right central portions of the plate rise above a concave curved plate bottom.

FIG. 2 is a bottom view of the bagel plate shown in FIG. 1. FIG. 3 is a right side view of the bagel plate shown in FIG. 1 (the left side view being a mirror image of the right side view); and,

FIG. 4 is a front view of the bagel plate shown in FIG. 1 (the bottom being a mirror image of the top view). The broken lines depict unclaimed portions of the bagel plate and form not part of the claim.
